METHOD OF FORMING ELECTRIC PLUG CONNECTORS

Frederick R. Reutter, Waterbury, Conn., assignor to Scovill Manufacturing Company, Waterbury, Conn., a corporation of Connecticut

Application January 11, 1938, Serial No. 184,399

3 Claims. (Cl. 29—155.55)

This invention relates to contactor prongs for electric plug connectors and particularly to the method of making such a prong.

The recent trend in the manufacture of this commodity is to make and market a plug connector in which the body part is made of a relatively soft rubber material which renders the article non-breakable and presents other advantages in the assembly of the unit. It is, therefore, one of the objects of this invention to make a suitable contactor prong that in being assembled to such a plug connector can be securely anchored therein with the minimum of effort and expense.

15 A further object is to make a contactor prong for the above use in which the original metal stock from which the prong is made is no wider than the finished width of the prong, this resulting in substantial economies in manufacture.

20 The portion of this prong which is embedded into the rubber stock is provided with locking elements which are forced or peened outwardly from the opposite longitudinal edges of the prong. This is effected by striking a forceful blow near the edge of the prong in such a manner as to drift or force the metal out of its normal bounds in the form of a relatively sharp barb. When the prongs are inserted into their respective sockets in the plug body, the sharp barbs become embedded within the rubber material locking the prongs therein and effectively preventing their withdrawal therefrom.

Other objects and advantages of the invention will be apparent from the following description which taken in connection with the accompanying drawing discloses a preferred embodiment thereof.

In the drawing:

Fig. 1 is a side elevation of a conventional form 40 of electric plug unit of the type in which the invention may be embodied.

Fig. 2 is a vertical section through the same, showing the manner in which the electrical connection is made between the prongs and conductors.

Fig. 3 is a transverse vertical section through the prong member taken on the line 3—3 of Fig. 2.

Fig. 4 is a fragmentary vertical section view taken on line 4—4 of Fig. 3.

Fig. 5 is a plan view of the prong member, per se, as it appears before the barb forming operation.

Fig. 6 is a perspective view of the contactor 55 prong in its finished state, and

Fig. 7 is a view similar to Fig. 2 of the body member, per se.

In the drawing the numeral 10 designates a plug body member made of relatively soft rubber material. The inner face end of the body member is provided with a recess 11 connecting with a central orifice 12 passing through the length of the body 10, and through which a twin conductor cable 13 may be inserted. Opening into the opposite ends of the recess 11 are a pair of 10 relatively narrow prong reception sockets 14, 14 extending in parallel for a substantial distance into the body 10. The sockets 14, 14 are adapted to receive and retain a pair of electrical terminal or contactor prongs 15, 15 in a manner to be 15 later described, the construction of the prongs being the principal substance of this invention. The two contactor prongs used in this device are identical and a description of one may stand for both. The manner in which this prong 15 is produced is best illustrated in Figs. 5 and 6. Herein the original blank indicated by the numeral 16 out of which the prong 15 is fabricated is shown in Fig. 5 of a width the same as the width of the metal stock. The metal stock out 25 of which the blank 16 is cut is shown in Fig. 5 in dotted outline and indicated by the letter X.

Adjacent one end of the blank 16, a pair of opposed slots 17, 17 are cut in from the opposite longitudinal edges. Specifically the slots 17, 17 30 are cut so that one sheared wall 18 is inclined to the longitudinal axis of the blank 16 while the opposite sheared wall 19 thereof is disposed substantially perpendicular to the axis of the blank. In order to produce a suitable means for locking 35 the prongs 15 in position within the body 10, provision is made of projections on barbs 20 extending beyond the opposite longitudinal edges of the blank 16. These barbs 20 are produced by supporting the blank 16 upon a suitable anvil 40 and giving the metal stock near the sheared wall 18 a severe blow with a rounded nose punch and creating a pair of sockets 21, 21 in the adjacent face of the blank. The concave sockets 21, 21 formed by the punch cause the metal so displaced 45 to be drifted or forced to the side, the metal traveling in the direction of least resistance, and by reason of the slots 17 the metal is virtually peened or extruded outwardly beyond the longitudinal edges of the blank, thus creating the barbs 20 above mentioned.

It is to be noted that the leading edges of the barbs 20 forced into the sockets 14 are disposed at an obtuse angle to the adjacent blank edges, 55

consequently permitting relative easy insertion of that end of the contactor prong 15 into the socket 14. The opposite wall of the barb 20 is disposed at an acute angle to the adjacent edge 5 of the blank 16, which condition disposes the barbs 20 to deeply embed themselves into the rubber material and crowd it into the slots 14, 14 and in consequence to lock said prongs in permanent assembly with the body more and more 10 securely as pressure is exerted to withdraw the prongs therefrom.

Figs. 3 and 4 show the condition in which the rubber is crowded into the slots 17 and also into the sockets 21 when in an assembled state. It 15 will be apparent from Fig. 3 that the greater the force exerted to pull the prongs out from their respective sockets the more effectively will the rubber material be jammed into the slots 17. Incidentally the sockets 21 form additional reception 20 chambers into which the rubber may be crowded as an added retaining and stabilizing factor.

The manner in which the assembly is effected is best shown in Figs. 2 and 3. The conductors 25 23 of the twin cable 13 are stripped of a substantial length of the insulation material at the inner end thereof, the cable first being inserted through the central orifice 12 of the body 10. Each prong 15 is provided with an intermediate 30 hole 24 and the inner end of the prong is provided with a terminal notch 25. To effect an electric connection between the conductors 23 and prongs 15 that portion of the conductor that is stripped 35 of insulation is inserted from the inner face of the prong 15 through the hole 24. The conductor 23 is then passed upwardly along the opposite face of the prong and finally bent around the end notch 25 with the end of the conductor 23 resting against the inner face of the prong 15. With 40 the conductor 23 so disposed the prongs 15 are then forcibly inserted into the sockets 14, the compression of the rubber material of the body naturally causing the strands of the conductor 23 to be firmly pressed against the opposite faces 45 of the prongs to assure a good electrical connection.

Various modifications will occur to those skilled

in the art as to other ways of producing locking means for plug contactor prongs, and no limitation is intended by the phraseology of the foregoing description or illustrations in the accompanying drawing except as indicated in the appended claims. 5

What is claimed is:

1. The method of producing a conductor prong for an electric connector plug of pliable material comprising cutting a longitudinal blank from a 10 strip of metal of the blank width, cutting a slot in from the longitudinal edge of said blank, one edge of said slot being cut at an acute angle and the opposite edge being cut substantially at a right angle to the axis of said blank, swaging a concave socket into the blank surface adjacent the right angle edge and thereby forcing the adjacent metal stock outwardly from the longitudinal edge of said blank into an angular barb. 15

2. The method of producing a conductor prong 20 for connector plugs comprising cutting a longitudinal blank from a strip of metal of the blank width, cutting a slot in from the longitudinal edge of said blank with one edge of said slot cut at an acute angle and the opposite edge at 25 a right angle to the longitudinal axis of said blank, swaging the metal stock adjacent the right angle edge of said slot in such a manner as to cause a barb to be extruded outwardly beyond the longitudinal edge of said blank and have 30 its sheared edge which was originally the right angle edge of said slot disposed at an acute angle to the axis. 35

3. The method of producing a conductor prong 40 for an electric connector plug of pliable material comprising cutting a longitudinal blank from a strip of metal of the blank width, slotting inwardly from the opposite longitudinal edges of 45 said blank, one edge of which slots is disposed substantially at right angles to the longitudinal axis of said blank, and forming depressed sockets in the surface of said blank adjacent said right-angle edges of said slots and thereby causing opposed barbs to be forced outwardly from the material of said blank beyond the longitudinal edges. 50
